UNITED STATES PATENT OFFICE.

JOSEPH C. VETTER, OF NEW YORK, N. Y.

INDUCTION-COIL FOR MEDICAL USE.

SPECIFICATION forming part of Letters Patent No. 330,531, dated November 17, 1885.

Application filed May 16, 1885. Serial No. 158,962. (No model.)

To all whom it may concern:

Be it known that I, JOSEPH C. VETTER, of the city and county of New York, in the State of New York, have invented a new and useful Improvement in Electro-Magnetic Instruments for Medical Use, of which the following is a specification.

The object of my invention is to provide a very simple induction-coil apparatus for medical use, and particularly for home use by inexperienced persons, in which is employed a simple sal-ammoniac battery. Such a battery is very desirable for use by inexperienced persons, because it does not require frequent cleaning and rinsing, as do batteries in which are used bichromate of potash, sulphate of copper, bisulphate of mercury, and other strong solutions, and because the sal-ammoniac solution is harmless to the parts of the instrument and to the persons using it, as compared with the stronger solutions. The sal-ammoniac battery is, however, of large size, as compared with the other batteries above referred to; and my invention has for its aim to provide an apparatus which is very compact and easily carried, and which has the induction-coil and all other parts contained and concealed within the case, but capable of adjustment from the outside of the case. These results are secured by the instrument or apparatus illustrated in the accompanying drawings; and the invention consists in novel combinations of parts, hereinafter described, and pointed out in the claims.

In the drawings, Figure 1 is a vertical section of an instrument or apparatus embodying my invention. Fig. 2 is a front elevation of the apparatus. Fig. 3 is a plan thereof, the top or cover of the case being removed and the electrodes withdrawn from the case; and Fig. 4 is an inverted plan of the core of the induction-coil and a top piece or stock from which it depends.

Similar letters of reference designate corresponding parts in all the figures.

A designates the case, which may be of wood, covered with leather or other material to give it an attractive appearance, and which has a top or cover, A', hinged at a, and held closed by a hasp and button, a' a'', or other suitable catch.

B designates the glass or other jar of an

ordinary sal-ammoniac battery having zinc and carbon or other equivalent elements. The zinc element has at its top a binding-screw, b, or 55 other suitable means of attachment for the conductor b*, and the carbon has a similar binding-screw, c, or other means of attachment for the conductor c*. The jar B is held in place between the back of the case A and retaining 60 strips or blocks C, which are held in place by upright cleats or ribs d, secured to the sides of the case. The jar is preferably supported or cushioned by corrugated paper or other elastic or yielding packing material, d*, at the 65 bottom and upright faces of the parts which hold it in place, as shown in Figs. 1 and 3. At the front of the jar B is an upright partition, A², which is or may be fixed in the case, and upon this rests a top piece or stock-piece, 70 D, made in the form of a small board or plate, of wood or other non-conducting material, from which depends the induction-coil E. The primary wires of this core are fixed in the top piece, D, and at the upper side thereof 75 are a vibrator, F, of suitable construction, sockets b' c', to receive the battery-conductors b* c*, and other sockets, e' e' e'', to receive the electrode-conductors, hereinafter described. The wires of the induction-coil E, the vibrator F, 80 and the several metallic sockets b' c' e' e' e'', above mentioned, are all suitably connected to produce the proper circuits by means of wires in or on the top piece, D, and as these wires or connections are well understood, and 85 may be arranged by any electrician, I have not thought it necessary to show them. The coil E depends in the compartment of the case forward of the partition A²; and G designates the metallic sleeve or tube, adjustable on the 90 coil, to vary the strength of the current.

In the front of the case is a slot, f, and an adjacent graduated scale, f', and in this slot is fitted a pin, g, projecting from the sleeve G, and having at the outside of the case a knob 95 or handle, g', and an attached pointer or indicator, g*. (Shown in Fig. 2.) By means of the pin g and knob g' the sleeve G may be slid up and down the coil E, to bring it to a definite desired position, to be determined by 100 the scale f', and the sleeve will be held in the position to which it may be adjusted by a spring, g², which is attached to the tube or sleeve G, and has frictional contact with the

inner side of the case, as shown in Fig. 1. A spring might be otherwise arranged to form a friction-brake to hold the sleeve after adjustment. The pin and knob $g' g$ constitute 5 a hand-piece for moving the sleeve or tube G.

As shown in Fig. 1, the sleeve or tube G is adjusted to its lowest position entirely clear of the coil E, and in order to prevent the sleeve from striking the end of the coil when 10 I place upon the coil a tube, E', which projects considerably beyond the lower end of the coil and downward well into the sleeve or tube G. This tube forms a guide to the sleeve G, and may be of paper or other non-conducting material. Paper is advantageous, 15 because it has little thickness. The upper end of the paper guide-tube E' may be turned outward, or "fringed" to form a flange, h, which is secured, by adhesive substance or 20 otherwise, to the under side of the top piece, D, as best shown in Fig. 4, but also in Fig.

1. When the sleeve G is raised to its top-most position, its upper end, if it strikes at all, will bear on the flange or fringed and spread 25 end h of the paper guide-tube E', and therefore will not make metallic contact with any wires which may be exposed on the under side of the top piece, D. In the rear edge of the top piece, D, which overhangs the partition A², are semicircular notches i, and in the space between the top piece and the jar B are slipped the electrodes H, they being confined by the said notches i. The electrodes H have attached conductors j, which are wound 30 around their handles when packed in the case, as shown in Fig. 1, and which may be placed in the sockets e' e' e² when the electrodes are in use, as shown in Fig. 3. At the back of the case A are corner-pieces k, in which are 35 sockets b² c², that receive the conductors b* c*, as shown by dotted lines in Fig. 3, when the apparatus is not in use, and from which the conductors may be withdrawn and inserted in the sockets b' c', as shown by full lines in 40 Fig. 3, when the apparatus is to be used. The corner-pieces k serve to stay the case, and by their sockets b² c³ hold the conductors and keep them from flying about when the apparatus is not in use.

50 By my invention I provide an apparatus of neat and attractive form, which may be conveniently carried and safely used by inexperienced persons, which is not expensive, has a sufficiently powerful battery for any 55 purposes to which it is adapted, and which has all parts, including the induction-coil, contained in the case.

In an apparatus of the form represented the

best place for the slot f, scale f', and index-knob g g* is in front of the case; but the position of these parts in and on the case will depend on the form of the case and the arrangement of the coil within it. 60

What I claim as my invention, and desire to secure by Letters Patent, is— 65

1. The combination, with a battery and a case therefor having in it a slot, of an induction-coil and sleeve or tube movable one relatively to the other and both contained within the case, and a hand-piece attached to the 70 movable part and projecting through and movable in said slot, substantially as herein described.

2. The combination, with a battery and the case therefor having in it the slot f and adjacent scale, of the depending induction-coil E and the sliding sleeve or tube G, with its pin and knob g' g movable in said slot, substantially as herein described. 75

3. The combination, with an induction-coil 80 and sleeve, one being movable lengthwise relatively to the other, of a non-conducting guide-tube projecting beyond the end of the coil and into the sleeve, substantially as herein described.

4. The combination, with the top piece, D, and the coil E, secured thereto, of the non-conducting guide-tube E', having the flange h at one end and projecting beyond the coil at the other end, and the adjustable sleeve G, 90 substantially as herein described. 85

5. The combination, with the jar B and case A, of the top piece, D, having semicircular recesses i, the induction-coil and sleeve E G, depending from and below the top piece, and 95 the electrodes H, arranged between the jar and top piece and confined by said recesses i, substantially as herein described.

6. The combination of the case A, the battery-jar B, with its elements and conductors 100 b* c*, and corner-pieces k at the back of the case, forming stays thereto, and provided with sockets b² c² for the conductors when not in use, substantially as herein described. 105

7. The combination of the case A, the jar 110 B, confined in place between the strips or pieces C and the back of the case, the top piece, D, with its depending induction-coil E, and the adjustable sleeve G therefor, and the electrodes H, arranged between the top piece, 110 D, and the jar, all substantially as described.

J. C. VETTER.
